UNITED STATES PATENT OFFICE.

JOHN GEORGE BUEHLER, OF NEW YORK, N. Y., ASSIGNOR TO COLUMBIA MACHINE CO., OF SAME PLACE.

ANCHOR FOR OVERHEAD WIRES.

SPECIFICATION forming part of Letters Patent No. 617,804, dated January 17, 1899.

Application filed September 1, 1898. Serial No. 690,008. (No model.)

To all whom it may concern:

Be it known that I, JOHN GEORGE BUEHLER, a citizen of the United States, and a resident of New York, in the county of Kings and State of New York, have invented certain new and useful Improvements in Anchors for Overhead Wires, of which the following is a specification.

The object of my invention is to provide an improved means for suspending the overhead wires for electric cars.

In the drawings forming part of this specification, Figure 1 is a perspective view of my improved anchor. Fig. 2 is a section taken on the line 2 2 of Fig. 1. Fig. 3 is a section taken on the line 3 3 of Fig. 1. Fig. 4 is a detail, partly in section, showing the attachment for the angle stay-wire. Fig. 5 is a view in perspective showing my device adapted for a support for double wires. Fig. 6 is a perspective view showing the anchor for double trolley-wires. Fig. 7 is a view, partly in section, showing a method of insulation for the connection for the stay-wire.

The double pullover A is made in the shape of an arm, the ends curved downward and bifurcated, as at B, for the attachment of the straight stay-wire connection C. On this pullover is a boss D, through which is drilled a hole for passage of the bolt E. The line-ear E' has the usual clamping or securing device a for attaching the line-wire b and has, in addition, at each end the perforated ears F and at its center the boss G, which is tapped to receive the screw-threaded end of the bolt E, which connects the pullover with the line-ear.

H is a side piece which is made with set-offs at the end, as shown, these set-off portions having holes for attachment of the connecting-pieces for angle stay-wires. Near each end of this side piece is a boss or projection I, tapped to receive the threaded end of the bolt J, by which means the line-ear and side piece are connected. The manner of this connection is clearly shown at the left in Fig. 3. The connection C, by which the straight stay-wires are connected to the pullover, is in one piece, cast or formed in any suitable way, having the general shape of two rings joined

at a point on their peripheries. (See Figs. 1 and 2.) One ring is placed in the bifurcation in the end of the pullover and secured by a bolt K. This connection is clearly shown in Fig. 2. The insulation is secured by the insulating bushings L, L', and L'' and the washers M M'. If desired, washers of insulating material may also be used under the head of the bolt and under the nut, as shown in Fig. 7. This makes a very light, compact, and strong connection and one that is easy to connect, disconnect, or repair.

The connection for the angle stay-wires consists of the piece N, having a hole O drilled at one end and the other end bifurcated, as at P. The bifurcated end is fitted over the end of the side piece and secured by a bolt Q, as clearly shown in Figs. 3 and 4. The method of insulation is the same as in the connection for the straight stay-connecting piece and is clearly shown in the above-mentioned figures of the drawings.

The advantages of this construction are many. The connection between the pullover and the line-ear allows them to be set at any angle, so that the device can be used either on straight lines or curves, and the connection is such that the pullover will move without undue strain, so that the straight stay-wires will always be in the same line. When the stay-wires, especially the angle ones, are attached directly to the line-ear, as is now the custom, they make a V-shaped recess or pocket. In case the trolley-wheel should jump from the wire it will be caught in said recess or pocket and the harp be pulled out or the wire and connection broken. With my construction this could not happen. The trolley would pass under the anchor without danger of catching, and consequently with no danger of injury either to the trolley or the overhead wires.

It will be obvious that the manner of constructing my anchor can be varied in many ways—as, for instance, the pullover and line-ear could be made in one piece or the whole device could be cast in one. In such case of course the self-adjusting feature would be lacking.

In Fig. 5 I have shown my invention adapt-

ed for a suspending device for double trolley-wires. The construction is the same as that heretofore described, save that the side piece H is replaced by a second line-ear H'.

5 In Fig. 6 I have shown my anchor adapted for the double-trolley system, having in this case two line-ears and two side pieces, the other features of construction being the same.

What I claim, and desire to secure by Letters Patent, is—

10 1. In a securing device for overhead electric wires, the combination of the double pullover, the line-ear connected thereto, the side piece connected to said line-ear and means on said pullover and side piece for attaching the stay-wires, substantially as described.

15 2. In a securing device for overhead electric wires, the combination of the double pullover, the line-ear connected thereto, the side piece connected to said line-ear, the ends of said side piece being offset, and means on said pullover and side piece for attaching the stay-wires substantially as described.

20 3. In a device for securing overhead electric wires the combination of the double pull-

over having downcurved and bifurcated ends, a line-ear attached to said pullover, a side piece attached to said line-ear, and means for attaching the stay-wires, substantially as described.

25 4. In a device for securing overhead electric wires the combination of the double pullover having downcurved and bifurcated ends, a line-ear yieldingly attached to said pullover, a side piece attached to said line-ear, and means for attaching the stay-wires, substantially as described.

30 5. In a securing device for overhead electric wires, the combination of the double pullover, the line-ear connected thereto, the side piece connected to said line-ear, and means on said pullover for attaching the stay-wires.

Signed at New York, in the county of New York and State of New York, this 25th day of August, A. D. 1898.

J. GEORGE BUEHLER.
